UNITED STATES PATENT OFFICE.

REINHOLD G. MARQUARDT, OF MILWAUKEE, WISCONSIN.

WOVEN-WIRE MATTRESS.

No. 923,286.

Specification of Letters Patent.

Patented June 1, 1909.

Application filed November 9, 1908. Serial No. 461,600.

To all whom it may concern:

Be it known that I, REINHOLD G. MARQUARDT, a citizen of the United States, residing at Milwaukee, county of Milwaukee, and 5 State of Wisconsin, have invented new and useful Improvements in Woven-Wire Mattresses, of which the following is a specification.

My invention relates to improvements in 10 woven wire mattresses, and it pertains more specially among other things to the device by which the following objects are accomplished: 1st. By which the slack of the mattress between the respective end bars of its 15 supporting frame is taken up from time to time as the mattress becomes stretched without moving said end bars; 2nd. by which the respective sides of the mattress are prevented from converging or being drawn inwardly toward the longitudinal center of the mattress by downward pressure upon its upper surface; and 3rd. by which one side of the mattress may be put under greater or less tension than the other and so adjusted 20 that it will remain level when used by a light and heavy person.

The construction of my invention is further explained by reference to the accompanying drawings, in which—

30 Figure 1 represents a plan view thereof. Fig. 2 is also a plan view of a modified form of one end of the mattress only, in which the turn buckles are dispensed with and the tension cables are tightened with an ordinary nut, having screw threaded bearing thereon.

Like parts are identified by the same reference figures throughout both views.

1 represents the longitudinal members of the mattress frame.

40 2, 2, are the end members.

3 represents a woven wire mattress of ordinary construction, which is connected at its respective ends with the ends of the frame. The mattress 3 is preferably provided at its

45 respective sides with cables 4, 4. The respective sides of the mattress are provided with tension cables 5, 5, and 6, 6. One of the ends of the respective cables 5 and 6 are permanently connected with one of the end members 2 of the frame, while the other ends of said cables are connected with the opposite end member of the frame by turn buckles 7 and screw threaded connecting rods 8, 8.

50 One end of the rods 8 are rigidly connected with the end of one of the members 2, while their opposite ends are provided with screw

threads for the reception of the screw threaded ends of the turn buckles 7. The opposite ends of the turn buckles 7 are provided with longitudinal apertures for the ends of the tension cables 5 and 6, which cables are inserted in said apertures and upset in such a manner as to permit the turn buckles to turn upon the end of said cables 5 and 6, as their opposite ends operate on the screw threaded 65 bearings of the rods 8. Thus it is obvious that by turning said turn buckles forwardly and backwardly upon their screw threaded bearings, the tension of the cables 5 and 6 may be increased or diminished. 70

The central portions of the cables 5 and 6 are connected with the mattress 3 by the loops 9, 9, and transversely arranged rods 10. The outer ends of the rods 10 are respectively connected with the cable 4 of the mattress, 75 whereby as the tension of said cables is increased, the central portion of the mattress will be forced outwardly until the mattress is given the desired tension. The fastening loops 9 may be formed integrally with or independently of the transversely arranged rods 10 and said loops serve to connect both the tension cables 5 and 6, as well as the rods 10 with the mattress. 80

In the modified form shown in Fig. 2, the 85 turn buckles 7 are dispensed with and the ends of the cables 11 extend through the end rails of the mattress and are provided with screw threaded bearings for the reception of the nuts 12, whereby it will be understood 90 that as said nuts are turned down on the ends of said cables against the surface of the end members 2, said cables will be tightened, while by a reverse movement, they will be loosened. It will also be understood that by 95 the device shown, the tension of either side of the mattress may be increased or diminished without increasing or diminishing the tension of the other side, whereby the same is adjusted as stated, to correspond with the 100 weights of different persons, and whereby the mattress may be maintained in a level position under different pressures. It will also be understood that the tension of the mattress may with my device be increased 105 or diminished without changing the relative position of the end bars to the side bars of the frame.

Having thus described my invention what I claim as new and desire to secure by Letters Patent, is—

1. In a device for manually increasing and

diminishing the tension of a woven wire mattress by forcing its central portions outwardly at right angles to its longitudinal center, the combination of a mattress frame 5 having stationary end members, a woven wire mattress permanently attached at its respective ends to the end members of the frame, a plurality of tension cables respectively connected at their ends to the end 10 frame members near the corners of said frame and extending from thence inwardly toward the longitudinal center of the frame, a plurality of transversely arranged rods respectively connected at one end with the central portion of said tension cables and mattress, and extending from thence outwardly and connected with the edge and at intermediate points with said mattress, and means for increasing and diminishing the 15 tension of said cable.

2. In a device for manually increasing and diminishing the tension of a woven wire mattress by forcing its central portions outwardly at right angles to its longitudinal center, the combination of a mattress frame 20 having stationary end members, a woven wire mattress permanently attached at its respective ends to the end members of the frame, a plurality of tension cables respectively connected at their ends to the end frame members near the corners of said frame and extending from thence inwardly toward the longitudinal center of the frame, a plurality of transversely arranged rods located upon the respective sides of the longitudinal center of the mattress and respectively connected at one end with the central portion of said tension cables and mattress, and extending from thence outwardly and connected with the edge and at intermediate points with said mattress, and turn buckles connected with said tension cables for increasing and diminishing their tension and the tension of the mattress, all substantially as and for the purpose specified.

25

3. In a device for manually increasing and diminishing the tension of a woven wire mattress by forcing its central portions outwardly at right angles to its longitudinal center, the combination of a mattress frame having stationary end members, a woven wire mattress permanently attached at its respective ends to the end members of the frame, a plurality of tension cables located upon the respective sides of the longitudinal center of said mattress and respectively connected at their ends to the end frame members near the corners of said frame and extending from thence inwardly toward the longitudinal center of the frame, a plurality of transversely arranged rods located upon the respective sides of the longitudinal center of the mattress, and respectively connected at one end with the central portion of said tension cables and mattress, and extending from thence outwardly and connected with the edge and at intermediate points with said mattress, and turn buckles connected with said tension cables for increasing and diminishing their tension and the tension of the mattress, all substantially as and for the purpose specified.

30

35

mediate points with said mattress, and turn buckles connected with said tension cables 40 for increasing and diminishing their tension and the tension of the mattress.

3. In a device for manually increasing and diminishing the tension of a woven wire mattress by forcing its central portions outwardly at right angles to its longitudinal center, the combination of a mattress frame 45 having stationary end members, a woven wire mattress permanently attached at its respective ends to the end members of the frame, a plurality of tension cables located upon the respective sides of the longitudinal center of said mattress and respectively connected at their ends to the end frame members near the corners of said frame and extending from thence inwardly toward the longitudinal center of the frame, a plurality of transversely arranged rods located upon the respective sides of the longitudinal center of the mattress, and respectively connected at one end with the central portion of said tension cables and mattress, and extending from thence outwardly and connected with the edge and at intermediate points with said mattress, and turn buckles 50 connected with said tension cables for increasing and diminishing their tension and the tension of the mattress, all substantially as and for the purpose specified.

In testimony whereof I affix my signature 55 in the presence of two witnesses.

REINHOLD G. MARQUARDT.
